COPYHOLDER

Nugent Dodds, Washington, D. C., assignor to
 Alfred M. Houghton, Washington, D. C.

Application November 20, 1940, Serial No. 366,486

8 Claims. (Cl. 120—29)

This invention relates to copy holders and more particularly to devices of that character in which succeeding lines of written text material are successively designated in a step-by-step manner for accurate reading by a copyist.

While there are a variety of known copy holders so constructed as to be subject to manipulation by an operator to present a selected line of written material in reading position, those which have enjoyed the widest commercial acceptance are characterized by a construction including two members; one of which serves to support the copy, while the other includes some line designating means. In such a machine, it is customary for one of the members to be held stationary, while the other is arranged for movement in a step-by-step manner to bring succeeding lines of copy into registry.

It is evident that, regardless of which one of the relatively movable members is actuated, the position thereof should, at all times, be completely under the control of the operator so as to insure accurate designation of any selected line of copy which, of course, will facilitate accurate reading of the material being copied. There are several factors which contribute to the production of a copy holder which may be controlled to the necessary extent. These include adjustment of the machine to accommodate successive lines of copy spaced different distances apart, the response of the machine to adjustment, and the maintenance of any selected line designation against vibration incident to the operation of a copy machine such as a typewriter or type setting machine with which the copy holder will be customarily associated.

It will be noted that each of the above control factors are incident to the operation of the machine in copy supporting position. However, since in the usual construction of a copy holder the relatively movable members mutually telescope, and since most copy holders are portable, that is, bodily movable, it is desirable that the control over the position of the movable member be continuous, regardless of whether or not the machine is in operation or whether it is being moved from place to place. Otherwise, the telescoping members might become disengaged as a result of handling in the course of transportation thereby rendering the re-assembly of the machine necessary before it can be used again.

The necessity for maintaining control over the movable member at all times when the machine is not in operation is of special advantage in some types of copy holders which have been recently developed. One such machine, disclosed in Dodds Patent 2,076,443, is adapted for specific use in conjunction with a typewriter. Copy is normally held in reading position rearwardly of, but above, the typewriter. The copy holder dis-

closed is intended for permanent installation on a typewriter desk and, as a consequence, means are provided whereby both the copy support and the line designating guide, as a unit, may be folded to a position rearwardly of the typewriter, but below the upper edge thereof, so that both the typewriter and the copy holder may be used in conjunction with a folding-type desk or may be protected by a dust cover of ordinary construction.

Since, in the patented device, both of the relatively movable members are moved as a unit from a vertical operative to a horizontal inoperative position, and since during such movement they may become extended to a degree which may prevent folding of the desk, it is evident that control over the movable member when the machine is in inoperative position may contribute considerably to the convenience of the operator in taking advantage of the folding construction.

It is therefore an object of this invention to overcome all of the foregoing disadvantages and to provide a copy holder including a movable member, the position of which is under the control of the operator at all times, regardless of whether the machine is in operative or inoperative position, and regardless of whether or not it is in a stationary position or being moved about.

By this invention, it is contemplated that the movable member of a copy holder may be adjusted to different amplitudes of movement, will respond accurately to the adjustment and will maintain any adjusted position against all vibrations incident to use in conjunction with copying apparatus.

It is a further object of this invention to automatically lock the movable member of a copy holder against disengagement from its support during transportation or incident to movement from an operative to an inoperative position.

Other objects and advantages of this invention will be apparent from a consideration of the following detailed description of a preferred embodiment thereof in conjunction with the annexed drawings wherein:

Figure 1 is a view in front elevation of a copy holder of the type which may be moved from a vertical operative to a horizontal inoperative position showing, in released position, a locking dog for holding the movable copy support in retracted position;

Figure 2 is a detail view of the locking dog shown in Figure 1 when biased to locking position;

Figure 3 is a view in side elevation of a part of the copy holder shown in Figure 1;

Figure 4 is a view in section taken along the line 4—4 of Figure 1 showing the lever for nor-

mally holding the locking dog in released position;

Figure 5 is a detail view of the cramping bars used for moving and holding the copy support, the holding bar being shown in gripping position;

Figure 6 is a detail view similar to Figure 5 but showing the lifting bar in gripping position;

Figure 7 is a detail view similar to Figure 5 but showing both cramping bars in released position;

Figure 8 is a perspective view showing the construction of the lifting bar;

Figure 9 is a perspective view showing the construction of the holding bar;

Figure 10 is a perspective view of the bar through which the cramping bars are operated.

Referring to the drawings in further detail, it will be seen that the copy holder of Figures 1, 3 and 4 is of the type shown in Patent 2,076,448 and is adapted for permanent attachment together with a typewriter to the moving panel of a folding desk.

The copy holder comprises a base 10, a vertical standard 11 and a copy support 12 mounted for vertical sliding movement on the standard.

Base 10 consists of a flat portion, adapted to rest on a supporting platform preferably with its forward edge disposed beneath the rear legs of a typewriter, not shown, and a vertically disposed plate 13. Plate 13 is adapted, when the flat portion of base 10 is disposed beneath a typewriter, to extend vertically in spaced relation to the rear thereof, and it is to this plate that standard 11 is attached.

Standard 11 consists of a rear plate 14 having channel guides 15 along its vertical edges, a bottom plate 16 and a top plate 17. An auxiliary plate 18 is attached to the rear face of plate 14 at 19 and 20, plate 18 being positioned parallel to but spaced from plate 14. The spacing between plates 14 and 18 is sufficient to accommodate the head of a bolt 21 which passes through and serves to join plate 18 to vertical plate 13. Thus, standard 11 is supported on base 10 by attachment of members 18 and 13.

When standard 11 and copy support 12 carried thereby are as a unit in vertical operative position, as shown in Figure 1, bottom 16 of standard 11 rests on the flat portion of base 10 forward of plate 13 while the edge of said bottom is slipped under gripping members 22, which may conveniently be stamped from base 10. In order to hold the standard in this position, a U-bar 23 is employed. This bar comprises a shank 24 serving as a handle, a shank 25 and a transverse shaft mounted for rocking movement in a barrel 26 attached at 27 to the rear face of plate 13. In the position shown in Figures 3 and 4, shank 25 acts as a cam to urge the entire standard in a direction away from plate 13 so that the forward edge of bottom 16 is held under and in engagement with gripping members 22. Movement of U-bar 23 in the direction of the arrow in Figure 3 will release the standard 11 and copy support 12 carried thereby. This release is effected so that the standard and support as a unit may be moved to a horizontal position lying below the upper edge of a typewriter in a manner to be herein-after described.

Copy support 12, which is mounted for sliding movement on standard 11, consists of a flat front plate 28 having channeled guides 29 along its vertical edges and a top plate 30. Guides 29 are of a contour corresponding to that of guides 15

and are adapted to fit thereover to permit relative sliding movement between members 11 and 12.

According to the construction shown, standard 11 is held stationary while copy support 12 is moved with respect thereto. As a consequence, a copy gripper is associated with copy support 12 while a line designating guide is attached to standard 11.

The copy gripper comprises primarily a flat bar 31 extending for the full width of front plate 28 of copy support 12 and a pair of L-shaped flat strips 32, one shank of which extends upwardly from either end of flat bar 31, while the other shank extends rearwardly across the top 30 of a copy support 12 in a plane at right angles to the plane of bar 31.

Strips 32, at their ends remote from bar 31, are connected by a barrel 33 which includes two downwardly projecting tabs 34. Each tab 34 is attached to a leaf spring 35 which in turn is attached at its other end 36 to the rear face of plate 28. Springs 35 are so adjusted that they normally tend to hold bar 31 against the front face of plate 28. It will be understood that in constructing the copy gripper bar 31, strips 32, barrel 33 and tabs 34 may be stamped from a blank and may thereafter be bent into the form shown in Figure 3. The flat surface of bar 31 which faces the front of plate 18 is provided with a continuous strip of resilient gripping material 37 which conveniently may be made of sponge rubber. A thumb rest 38 is attached to the center of top wall 30 of member 12.

Barrel 33 has detachably received therein one shank of a U-bar 39. This bar is mounted for pivotal movement about barrel 33 as an axis, the free shank extending rearwardly of plate 14 of standard 11.

When copy is to be held on supporting member 12 in reading position, the operator may grasp barrel 33 and thumb grip 38 with his fingers and force them toward one another. This will result in compression of springs 35 and the forward movement of strips 32 and bar 31 carried thereby. Thus, bar 31 will be moved away from the face of plate 28. Once gripping strip 37 and the front face of plate 13 are spaced apart sufficiently to accommodate a sheet or sheets of copy therebetween, such copy is inserted and an edge thereof is pushed up until it comes to rest against the lower surface of the shanks of strips 32 which are at right angles to the long axis of the plate 28 and hence to the paper held thereagainst. These shanks of strips 32 serve to align the paper on the supporting member 12 for the reason that they lie in a plane parallel to its top 30. Once the paper is in position, thumb grip 38 and barrel 33 are released. Springs 35 then move to normal position (as shown in Figure 3) thereby compressing the sheet or sheets of copy between gripping strip 37 and the front face of plate 28. Since gripping strip 37 is continuous for the full length of bar 31, the copy will be held firmly in aligned position during the ordinary manipulation of the copy holder.

If material is to be copied from a sheet of a bound volume, such as a stenographer's notebook, the top edge of bar 31 is used as a sight line to align the copy while pages not in use may be thrown back over top 30 and held against back plate 14 of standard 11 by the free arm of U-member 39. Since U-member 39 is mounted for pivotal movement in barrel 33, the distance

of the free arm thereof from plate 14 may be adjusted to accommodate any number of sheets up to a cumulative thickness equal to the length of the radial arm of the U-member.

Since the material to be copied is held between gripping strip 37 and the front plate 28 of the copy supporting member, it will hang downwardly parallel to the front face of plate 28. In order to designate a particular line to be read, a line designating guide 40, is employed. Guide 40 is mounted to extend across the face of plate 38 in spaced relation with respect thereto. Guide 40 consists of a flat strip having a barrel along one of its long edges. One shank of a U-bar 41 is mounted in this barrel while the other shank is pivotally mounted in a barrel 42 attached at 43 to the rear face of plate 14 of the supporting standard. When copy is being attached to the copy support plate 12 and it is desirable to have line designating guide 40 out of the way, U-bar 41 is moved about its axis in barrel 42 until the radial arm thereof is substantially at right angles to the long axis of plate 28. This will leave ample space between plate 28 and the line designating guide to permit easy adjustment of the paper in the manner heretofore described.

As has been stated, the copy holding member 12 is mounted for movement on standard 11. The purpose of this movement is to lift the copy held against plate 28 so that successive lines thereof may be presented to the line designating guide 40.

The actuation of copy support 12 is effected by manual operation of a lever 44 which will move a U-shaped lifting bar 45 which in turn lifts cramping bar 46 which acts on a rod 47 attached to copy support 12.

Operating lever 44 includes an arm 48 acting as a handle, a shaft 49 mounted for rocking movement in barrel 50, attached at points 51 to base 10, and a driven arm 52. The downward movement of arm 48 is limited by an adjustable cam 53 the structural details and operation of which may be found in Dodds Patent 2,076,448. The movement of arm 48, limited by the setting of cam 53, will be imparted to driven arm 52 through shaft 49. Arm 52 is connected to a shank 54 of U-shaped lifting bar 45, the shank being provided with a slot 55 for this purpose (see Figure 10). It will be noted that slot 55 has its mouth opening to the left side of shank 54 as viewed in Figure 1.

The other shank of U-shaped lifting bar 45, designated by the numeral 56, is mounted for vertical reciprocating movement in two shelf-like members 57 and 58 attached at 59 and 60, respectively, to rear plate 14 of standard 11. Each of the members 57 and 58 is provided with a rectangular slot 61 and 61a, respectively, adapted to receive shank 56. Both slots are of a length in excess of the width of shank 56 and the slot 61 in member 57 is open at one end (see Figure 4).

From the construction thus far described, it will be seen that downward movement of arm 48 of operating lever 44 will cause upward movement of driven arm 52 and that this upward movement will be imparted to U-bar 45 through the top edge of slot 55 in shank 54. Since U-bar 45 is of unitary construction, movement of shank 54 thereof will also result in movement of shank 56. This shank, acting through cramping bar 46, will lift copy support 12 through lifting rod 47 attached thereto.

Referring now to Figures 5 to 10, inclusive, it will be observed that cramping bar 46 is provided with a rectangular aperture 62 at one end thereof and at the other end with a round aperture 63. Aperture 62 is intended to receive a neck of reduced width 64, formed near the free end of shank 56, as shown in Figure 1, while aperture 63 loosely accommodates lifting rod 47. Apertures 62 and 63 are spaced apart a distance such that the edge of aperture 62 nearest aperture 63 will be held closely against neck 64. Above neck 64, shank 56 widens to form a portion 65 which extends in the direction of rod 47 in a position above cramping bar 46. The flat under surface of this portion extends at a right angle to neck 64. Thus, cramping bar 46 is pivotally attached to neck 64 of shank 56 and clockwise movement thereof is limited by rod 47, as can be seen in Figure 6, while counterclockwise movement is limited by portion 65 in the manner shown in Figure 7.

Another cramping bar 66, shown in Figure 9, is associated with rod 47 and shank 56 although it is attached to neither. Cramping bar 66 rests on support 67 suitably attached at 68 to shelf 58. In this position shank 56 passes freely through forked end 69 thereof while an aperture 70 freely accommodates rod 47. Since bar 66 is mounted for rocking movement about support 67 and since most of its weight is on the right side of the point of support as viewed in Figures 5 to 8, inclusive, its normal position is that shown in Figure 5. Forked end 69 of cramping bar 66 is bent upwardly so that straightening of bar 66 through portion 65 will be imparted thereto (see Figure 7).

The lifting rod 47 on which cramping bars 46 and 66 act is provided with a threaded end 71 of reduced diameter. This end is passed through a suitable aperture in top 30 of copy support 12, while connection is effected by a nut 72. On the under side of top 30, a resilient sleeve 73 surrounds the rod. While the copy support 12 is guided by the coaction of guides 15 and 29, a cylinder 14 is provided for the reception of rod 47. This cylinder is suitably attached to shelf 58 and bottom plate 16 and serves to receive the free end of rod 47 which passes through a suitable opening in shelf 58.

It has been explained that shank 56 may be caused to move upwardly by operation of lever 44. When this lever is released, shank 56 is returned to normal position by a spring 75 extending from shelf 57. Normal position for shank 56 is determined by a leaf spring 76 which is attached at one end to bottom plate 16 with its free end underlying the transverse portion of U-bar 45 and serving to space the same from bottom 16.

When the copy holder is to be operated, copy is attached to support 12 in the manner heretofore described. Cam 53 is adjusted to limit the movement of lever 44. At the start of operation, both cramping bars are in their normal position (see Figure 5). If operating lever 44 is now pressed down, the motion thereof will be transmitted in the manner heretofore explained to shank 56 of U-shaped lifting bar 45. Because of its weight, supported only from the end having aperture 62 therein, cramping bar 46 will be biased in the position of Figure 5. In that position the axis of aperture 63 is at an angle to the axis of rod 47 so that the defining edges of the aperture frictionally engage the rod. Thus, the upward movement of shank 56 will be imparted, without lost motion, through the shoulders there-

of at neck 64 to rod 47 which will lift copy support 12, thus bringing another line of copy into registry with line guide 40. Before lever 44 is operated, cramping bar 66 is also in the position of Figure 5, that is, gripping the rod 47. Upon upward movement of the rod, however, by action of cramping bar 46, bar 66 will be lifted by rod 47 to release position. This occurs by pivotal movement around support 67, the forked end 69 being free.

When operating lever 44 is released, spring 75 immediately returns U-bar 45 to normal position resting on spring 76. As this happens, cramping bar 66, which has been only slightly straightened by the upward movement of rod 47, immediately falls to gripping position as shown in Figure 5. During the downward movement of shank 56, portion 65 keeps bar 46 in release position but once the downward movement ceases, bar 46 also falls to the Figure 5 position and is again ready to lift rod 47 when lever 44 is next operated. Meanwhile, the adjusted position is continuously maintained by cramping bar 66.

It will be seen that if the foregoing procedure were repeated enough times, copy support 12 might be entirely separated from standard 11. To prevent this a locking dog 77 is pivotally attached to rear plate 14 of standard 11 near the top edge thereof. A spring 78 normally urges this dog to extended position through an aperture 79 in guide 15 and thus into engagement with the under side of guide 29. Near the lower end of guide 29 an aperture 80 is provided. Thus, when copy support 12 is moved to such an extent that apertures 79 and 80 are in registry, dog 77 will be urged by spring 78 through both of them, thereby locking standard 11 and copy support 12 against further relative movement. The dog 77 may be released manually.

When copy support 12 is to be lowered, operating lever 44 is pulled upwardly, thus causing arm 52 to move U-bar 45 downwardly below normal position thereby compressing spring 76. The effect of this movement on cramping bars 46 and 66 is illustrated in Figure 7. Portion 65 maintains bar 46 straight, in release position, while bar 46, acting on the ends of fork 69 pivots bar 66 to release position. Thus, when the cramping bars 46 and 66 are in the position of Figure 7, copy support 12 will not be held by either of them and so will fall by gravity to fully retracted position. The fall is cushioned by sleeve 73 which will insure noiseless operation.

In the fully retracted position of copy support 12, aperture 80 in guide 29 is aligned with another aperture 81 located near the lower end of guide 15. A double dog is pivotally mounted on back plate 14 in such a position that projection 82 may pass through openings 80 and 81 to lock together copy support 12 and standard 11. A spring 83 normally biases the projection 82 to this position. Another projection 84 extends through an opening 85 near the bottom of guide 15 at a point below the lower edge of copy support 12 even in its fully retracted position. Projection 84 lies in the path of handle 24 of U-bar 23 in its movement to normal position. Thus, when standard 11 is locked to base 10, by action of cam arm 25 which forces the forward edge of bottom 16 under grippers 22, projection 84 will be engaged and retracted by handle 24. Since the double dog is of unitary construction, retraction of projection 84 also results in retraction of projection 82 against the thrust of spring 83. As

a consequence the double dog does not serve to lock together standard 11 and copy support 12 except at such times as handle 24 may be in release position. Handle 24 is moved to release

5 position only when the copy support and standard are, as a unit, to be moved to horizontal inoperative position. Thus, projection 82 in no way interferes with the normal operation of the copy holder, but as the device is moved to horizontal position, the lock takes effect to prevent accidental separation of copy support 12 from its standard 11.

Movement of the standard and copy support to inoperative position involves first releasing cam 15 arm 25, then disengaging bottom plate 16 from grippers 22 and finally moving copy support and standard, as a unit, in a counterclockwise direction to horizontal position. It will be noted that auxiliary plate 18 is provided with a generally 20 C-shaped slot which guides the movement to and from horizontal position. This slot allows the left guide 29 to contact the upper surface of the flat portion of base 10 when the device is folded. In this position, the copy holder will not extend 25 above the edge of a typewriter with which it may be used. Return to vertical position is also guided by the slot in plate 18. However, even when the bottom of standard 11 has been urged into contact with grippers 22 and lock 82 has been 30 released, the device is not yet ready for operation. It will be seen that when slot 55 of shank 54 is disengaged from arm 52 of the operating lever, the latter will fall by gravity until cam 53 touches the surface of the support for the copy 35 holder. This raises the end of arm 52 above the slot so that return of standard 11 to vertical position will cause arm 52 and shank 54 to contact at a point above slot 55. Since arm 52 cannot be shifted laterally, U-shaped lifting bar 45 will 40 pivot about slot 61a as an axis to the position shown in broken lines in Figure 1. If lever 44 is then lifted so that arm 52 is lowered and aligned with slot 55, spring 75 will move the lifting bar back to normal position.

From the foregoing, it will be seen that the operator has complete control of the movement of copy support 12 at all times. Either one or the other of cramping bars 46 and 66 or dog 77 or 82 is serving to prevent undesired movement of the copy support. Of course, it is to be understood that the construction explained above is merely exemplary and that many modifications thereof be within the scope and spirit of the annexed claims.

What is claimed is:

1. In a copy holder including a base, mutually telescoping members, one of said members being adapted to hold copy and the other including line indicating means, means for moving one of said members to designate a selected line of copy, and means carried by one of said members and the base for positioning said movable members as a unit in either a vertical operative or horizontal inoperative position, means for locking said members against relative movement in any relative position when they are as a unit in vertical operative position, means for holding said members as a unit in vertical operative position, and means controlled by said holding means for locking said members against relative movement when they are as a unit in horizontal inoperative position, whereby the movable member may be held in fixed position regardless of whether the mem-

bers are as a unit in vertical operative or horizontal inoperative position.

2. In a copy holder including a base, mutually telescoping members, one of said members being adapted to hold copy and the other including line indicating means, means for moving one of said members to designate a selected line of copy, and means carried by one of said members and the base for positioning said movable members as a unit in either a vertical operative or horizontal inoperative position, means for locking said members against relative movement in any relative position when the two are as a unit in vertical operative position, releasable means for holding said members as a unit in vertical operative position, and means brought into operation by release of said holding means for locking said members in fully retracted position against relative movement when they are as a unit in horizontal inoperative position, whereby the movable member may be held in fixed position regardless of whether the two members are as a unit in vertical operative or horizontal inoperative position.

3. In a copy holder including a base, mutually telescoping members, one of said members being adapted to hold copy and the other including line indicating means, means for moving one of said members to designate a line of copy, and means carried by one of said members and the base for positioning said movable members as a unit in either a vertical operative or horizontal inoperative position, means for locking said members against relative telescoping movement upon full extension thereof, means for locking said members against relative movement upon complete retraction thereof, and means for locking said members against relative movement in positions intermediate full extension and full retraction, only when the movable members are as a unit in vertical operative position, whereby the movable member may at all times be held in fixed position with respect to the other member regardless of whether said members as a unit are extended in vertical operative or retracted in horizontal inoperative position.

4. In a copy holder including a base, mutually telescoping members, one of said members being adapted to hold copy and the other including line indicating means, means for moving one of said members to designate a line of copy, and means carried by one of said members and the base for positioning said movable members as a unit in either a vertical operative or horizontal inoperative position, automatic means for locking said members against relative telescoping movement upon full extension thereof, means under the control of the operator for locking said members against relative movement upon complete retraction thereof, and automatic means for locking said members against relative movement in positions intermediate full extension and full retraction only when the movable members are as a unit in vertical operative position, whereby the movable member may at all times be held in fixed position with respect to the other member regardless of whether said members as a unit are extended in vertical operative or retracted in horizontal inoperative position.

5. In a copy holder including a base, mutually telescoping members, one of said members being adapted to hold copy and the other includ-

ing line indicating means, means for moving one of said members to designate a line of copy, and means carried by one of said members and the base for positioning said movable members as a unit in either a vertical operative or horizontal inoperative position, releasable means for holding said members as a unit in vertical operative position, and means for latching said members against relative movement, said latching means being held inoperative by said releasable means only when it is in holding position, whereby upon release of said holding means said members will be locked together for movement as a unit to horizontal inoperative position.

15 6. In a copy holder including a base, mutually telescoping members, one of said members being adapted to hold copy and the other including line indicating means, means for moving one of said members to designate a line of copy, and means carried by one of said members and the base for positioning said movable members as a unit in either a vertical operative or horizontal inoperative position, releasable means for holding said members as a unit in vertical operative position, and means for latching said members against relative movement upon complete retraction, said latching means being held inoperative by said releasable means only when it is in holding position, whereby upon release of said holding means said members will be locked together for movement as a unit to horizontal inoperative position.

20 7. In a copy holder including a base, mutually telescoping members, one of said members being adapted to hold copy and the other including line indicating means, means for moving one of said members to designate a line of copy, and means carried by one of said members and the base for positioning said movable members as a unit in either a vertical operative or horizontal inoperative position, releasable means for holding said members as a unit in vertical operative position, and a spring urged dog for latching said members against relative movement upon complete retraction, said latching means being held inoperative by said releasable means only when it is in holding position, whereby upon release of said holding means said members will be locked together for movement as a unit to horizontal inoperative position.

25 8. In a copy holder including mutually telescoping, relatively movable members, one adapted to hold copy and the other to designate a selected line thereof, a lifting bar, means for moving the same longitudinally in either direction, and a lifting rod attached to one of the telescoping members, a friction clutch pivotally carried by said bar and adapted to engage said rod upon upward movement of said bar to transmit the motion thereof to said rod, means on said bar for releasing said clutch upon downward movement of said bar, a second clutch underlying the first and adapted to hold said rod when said bar is not moving in either direction, said second clutch including an upwardly canted bifurcated portion between the shanks of which said lifting bar is adapted to pass, and means supporting said second clutch between its ends for rocking movement to and from gripping position, whereby when the bar is moved downwardly the effect of the means for releasing said first-named clutch is transmitted therethrough to the second clutch to release the same.

NUGENT DODDS.
